STEAM ATTACHMENT FOR FLATIRONS

John N. Polivka and Maurice H. Graham, Minneapolis, Minn., assignors to General Mills, Inc., a corporation of Delaware

Application October 11, 1948, Serial No. 53,902

8 Claims. (Cl. 38—77)

1

This application relates to steaming devices and more particularly to steaming devices for attachment to an ordinary flatiron.

Various devices have been proposed for use in combination with a regular flatiron in order to provide steam during the ironing operation. Some of these devices or attachments are designed to convert water from a suitable source of supply into steam within the attachment and direct the steam into the material being ironed. Other devices are designed for connection to an external source of steam and serve either to superheat the steam or maintain it in its condition of vaporization while the steam passes through the attachment. Because such devices are separable from the flatirons with which they are used, it is sometimes difficult to maintain the parts in good heat conductive relationship with each other. We have found that the problems of proper heat conduction are intensified in many cases, by differences in the thermal expansion characteristics of the flatiron and the attachment and by variations in the dimensions of the parts within the normal manufacturing tolerances.

A number of methods have been proposed for attachment of such a steaming device to a flatiron. Some of the attaching means include the use of rigid clamps or screws which grip the iron firmly at spaced points. These clamps have the disadvantage that they are fixed and unyielding and cannot accommodate changes in expansion or position of the parts which may take place during heating. If they are set loosely enough to permit such relative expansion, then proper heat conduction cannot be obtained.

In other cases the attachment has been provided with springs or resilient strips passing over the top of the flatiron body to hold the attachment in assembled position. Such fastenings are bulky and unsightly and can be accidentally deformed or disengaged by external forces. Furthermore, in cases where the attachment includes a liquid supply tank, the use of such springs or strips makes it difficult to secure a compact location of the tank around the top portions of the iron, since considerable free space must be available for manipulation and engagement of the clamping springs. Also the goods being ironed tend to catch in any such externally accessible clamping means.

With these problems and difficulties of the prior constructions in view, it is one object of the present invention to provide an improved steam attachment for detachable connection to the bottom of an ordinary flatiron.

2

It is a further object to provide such a device with means for attachment to the iron which will accommodate differences in relative expansion or differences in length of the individual parts due to manufacturing variations without disturbing the necessary heat conductive relationship of the parts.

It is another object to provide improved means for attaching a steaming device to a flatiron which has a beveled or outwardly and downwardly sloping edge portion at both the front and the rear of the iron.

Still another object is the provision of an attachment for use with an iron having a beveled sole-plate edge; in which the attachment has an inclined cam portion for engaging the beveled edge at one end of the iron and a resiliently adjustable cam portion for engagement with the beveled edge at the opposite end of the iron.

A further object is the provision of an improved combination of parts in which such a steaming device includes a liquid supply tank and attaching mechanism compactly arranged for efficient connection to a flatiron.

A still further object is the provision of improved fastening means supported and concealed beneath the tank of such an attachment.

Another object is a steaming device in which a tank is carried by a support at one end of the device, said support also serving to carry and conceal the fastening mechanism by which the device is attached to a flatiron.

Other objects and advantages of the invention will be apparent from the following specification in which a preferred embodiment of the invention has been described by way of example.

In the drawings which form a part of this specification,

Fig. 1 is a side elevation of a steaming device attached to a flatiron.

Fig. 2 is a partial perspective view of the attachment of Fig. 1 removed from the flatiron.

Fig. 3 is a partial plan view of the attaching mechanism at one end of the flatiron.

Fig. 4 is a sectional view on the line 4—4 of Fig. 3, and

Fig. 5 is a partial sectional view showing how the fastening mechanism of the present invention accommodates relative differences in expansion or length of the parts.

In Fig. 1, the steaming device 10 is shown in position below a flatiron 12. The flatiron itself includes the customary soleplate 14 which is heated by an electrical resistance element (not shown). A cover or housing 16 conceals and protects the internal parts of the iron. A handle

18 provides means for manipulation of the iron and a control knob 20 may be mounted on this handle and connected to a control device within the shell 16 to regulate the temperature of the iron in known manner. An electric supply cord 22 furnishes the necessary current for the heating element.

The steaming device itself includes a steam soleplate 24 which is provided with a steam generating or heating chamber 26 and openings 28 through which the steam may be discharged from chamber 26 through the bottom of soleplate 24 and into the material being ironed. In this particular case, a conduit 30 supplies water to the chamber 26 from a reservoir or tank 32 mounted on a supporting member including side brackets 34 and 36 at the rear of steam soleplate 24. These brackets have horizontal lower flanges 35 and 37 which are attached to the soleplate 24 by suitable screws 38 (Fig. 2). The rear end of the soleplate has been recessed to fit these lower flanges, so that the upper surfaces of the flanges will lie flush with the top of the soleplate and provide an unbroken surface for engagement with the flatiron bottom. The side brackets 34 and 36 may be connected at their rear by an integral cross flange 39, so that the support is in substantially the form of a hollow column, open at the forward side.

In order to obtain proper vaporization or heating of the steam and at the same time maintain the steam soleplate 24 at a high enough temperature for satisfactory ironing purposes, it is necessary to establish good heat conductive relationship between the steam soleplate 24 and the bottom of the flatiron soleplate 14. The improved attaching mechanism according to the present invention is designed for use with a flatiron, such as the one illustrated, which is provided with outwardly and downwardly sloping or beveled portions at opposite ends or sides of the iron. In this case the beveled portions are provided on the edges of the soleplate 14. Thus the forward portion of the soleplate is beveled as indicated at 40. A fixed attaching member or toe box 42 is located at the forward end of the steam soleplate 24 for cooperative engagement with the beveled forward edge 40 of the flatiron soleplate 14. As shown in Fig. 5, the inner face of this retaining portion 42 is sloped at 44 to correspond to the beveled edge 40 at the front of the flatiron. Thus the portions 40 and 44 cooperate with each other to provide cam surfaces which will hold the bottom surface of flatiron soleplate 14 firmly against the top surface of steam soleplate 24 at their respective forward ends, in response to a movement or force tending to urge the flatiron soleplate to the left in Fig. 5 relative to the steam soleplate 24. Thus relative longitudinal movement between the flatiron and steam attachment in one direction tends to urge the forward portions of the flatiron and steaming device into firm heat conductive contact, in response to the camming effect of surfaces 40 and 44.

To provide this relative longitudinal movement, a resilient retaining member 46 is mounted at the opposite end of the steaming device for engagement with the opposite or, in this case, the rear end of the flatiron 12. Latch member 46 has a pair of latching arms 48 which cooperate with the outwardly and downwardly beveled rear edge portion 50 of the flatiron soleplate 14, as shown particularly in Figs. 3 and 4. In this case, the rear of the flatiron soleplate tapers to a smoothly rounded rear end or point, and the two latching

portions 48 engage the beveled edge 50 at opposite sides of the longitudinal center line of the soleplate 14. Thus the latch portions 48 serve to center the rear portion of the flatiron with respect to the attachment and to prevent relative lateral movement between these parts, just as the engagement of the sides of the fixed attaching member 42 prevents relative lateral movement between the front ends of the flatiron and steam attachment.

The latch member 46 consists of a relatively heavy wire or rod-like member, the ends of which are bent to extend transversely as indicated at 52 and 54 to provide bearing portions pivotally mounted in transverse openings in the tank supporting brackets 34 and 36 respectively. Bearing shaft 52 is extended on beyond the bracket 34 for connection to a suitable handle or finger piece 56 for manual operation of latch 46.

A relatively strong spring 58 (Fig. 2) is coiled about the bearing shafts 52 and 54 and has its intermediate portion in engagement with the central portions 60 of the latch member. The ends of the spring bear against suitable portions of the brackets or the tank in such a manner that the spring tends to urge the latch portions 48 downwardly toward the bottom of the attachment. The spring is omitted in Fig. 3 for clarity.

In operation of the device according to this invention the fingerpiece 56 will be operated to raise the latching portions 48 so that the rear end of the flatiron may be introduced underneath the latch. The forward end of the iron is then engaged with the steam attachment and the iron is moved forwardly so that the surfaces 40 and 44 at the front of the iron and attachment are in engagement with each other. Upon release of the fingerpiece 56 the spring 58 will urge the latching portions 48 downwardly against the beveled rear edge portions 50 of the flatiron. Since the edge portion 50 slopes outwardly both to the rear and to the side at this particular region of the iron, it is clear that a downward force on the latching portions 48 will exert a camming action against the surfaces 50 tending to urge the flatiron soleplate 14 forwardly relative to the steaming device. Thus the necessary relative longitudinal movement between the flatiron and steam attachment is provided. This will cause cooperating cam action between the inclined inner surface 44 of the fixed support 42 and the beveled forward edge 40 of the flatiron. The relative longitudinal force exerted by the resilient latch thus results in a tight clamping action at the forward end of the iron.

At the same time, the downward force exerted by the latching portions 48 against the surface 50 results in relatively tight clamping of the rear portions of the flatiron and steam attachment. It will be noted, accordingly, that the resilient latch 46 cooperates with the beveled rear portion of the flatiron soleplate 14 to provide an attaching force having two components. One component is exerted in a longitudinal direction and is utilized in cooperation with the sloping forward cam portions 40 and 44 to effect the necessary clamping at the front of the iron. The other component of force is vertical and serves to clamp the rear portions of the iron and steaming device.

As shown in the drawings, the sides of the tank supports 34 and 36 form smooth walls which extend forwardly beyond the forward edge 48 of latch member 46, as well as rearwardly beyond the shafts 52 and 54 of the latch. Thus the

latch is substantially concealed and protected inside the support portions 34, 36 and 39. This construction not only makes possible the design of an attachment which is more pleasing in appearance, but also prevents accidental deformation or damage to the latching portions by external forces. Furthermore the construction is exceedingly compact, since the tank may be located closely around and over the top rear portion of the iron, without the problem of obtaining access to the top of the iron for fastening the earlier type of top strap or spring. In this connection it will be noted that the tank has portions 33 extending forwardly along each side of the rear handle post to increase the tank capacity without substantial increase in the bulkiness of the assembly and without interference with the visibility of the forward and side portions of the ironing surfaces. These tank portions 33 also extend forwardly and laterally beyond the latch portions 48, so that the latch is further concealed and protected by the tank. Such protection and concealment are also obtained at the rear by rearward extension of the tank beyond cross flange 39 of the support.

The manner in which the attaching mechanism just described serves to maintain the flatiron and steam attachment in close heat conductive relationship at all times, regardless of differences in thermal expansion or differences in length resulting from manufacturing variations, is illustrated in Fig. 5. Here it may be assumed that the heavy line positions in the figure indicate the relative location of the parts when cold. At this time, the latching portions 48 engage the beveled rear surfaces 50 of the flatiron soleplate 14 at a given point 64 which is located between the top and bottom of soleplate 14. Thus there is a portion of surface 50 both above and below the point of engagement 64 of the latch 48. If the parts are now heated and if the steam attachment soleplate 24 expands more than the flatiron soleplate 14, the relative location of the rear of the steam soleplate 24 will be shifted to the dotted line position indicated at 66. Since latch portions 48 are pivoted to the supporting brackets on the rear of the steam attachment, the latch 48 will likewise be shifted to a new relative position a corresponding distance to the rear of its original location. Since, however, the latch 48 is resiliently urged in a downward direction, it will slide downwardly along the outwardly beveled surface 50 and will hold the flatiron soleplate 14 firmly against the front retaining cam 42. The final location of the latching member 48 may be represented by the dotted line position of Fig. 5 at which point the latch engages the surface 50 at a lower level 68 than the initial point of engagement 64. The resilience of the latch and its cooperative engagement with the sloping cam surface or beveled edge 50 of the flatiron has accordingly permitted the necessary difference in relative expansion of the parts while at the same time the horizontal and vertical components of force maintain the necessary clamping engagement at both the front and the rear of the flatiron and steam attachment.

Obviously if the flatiron itself expanded more than the steam soleplate, the situation would be reversed and the latch 48 would move upwardly and forwardly along the beveled portions 50 to maintain the proper clamping forces.

This latching mechanism likewise maintains the requisite clamping engagement in spite of

variations in the dimensions of the parts due to manufacturing tolerances. Thus the latch portions 48 are initially designed to engage the sloping edges 50 at substantially the vertical midpoint of these surfaces when both the flatiron and attachment are made exactly according to dimension. A slight variation one way or the other in the dimensions of either part will accordingly be accommodated by slight upward or downward shifting of the latch portion 48 from one iron or attachment to another.

The above action is made possible by the resilient camming engagement between the latch member and the beveled edge of the flatiron. It will be clear that this engagement requires that the latching portions 48 be movable along a line angularly intersecting the beveled soleplate edge. This condition can be met in a number of ways, whether the latch be pivotally or slidably mounted, by suitable location of the latch pivot or by adjustment of the latch mounting to secure the necessary line of action and camming engagement.

From the foregoing description, it will be apparent that a construction has been provided by which the objects of the present invention have been accomplished. The cooperative combination of fixed latching portions having cam interengagement at one end of the iron and attachment and of a resilient latching member at the opposite end of the attachment for cooperative engagement with a cam portion at the rear of the iron makes it possible to maintain a steam attachment in proper heat conductive relationship with a flatiron at all times. The contact is not disturbed by differences in the thermal expansion of the flatiron and steam attachment nor is it affected by small variations in dimensions due to manufacturing tolerances. It is therefore possible to produce such steam attachments in relatively large quantities with all the usual savings of mass production methods, without the problem of individual fitting or adjustment of each attachment to the particular iron with which it is designed for use. Furthermore, the arrangement of the tank on a support at the rear of the steam soleplate, and the mounting of an attaching member within the support and beneath the tank, offer definite advantages in compactness, appearance, ease of operation and economy of manufacture.

Obviously, variations in the specific details of construction of the parts and the manner in which they engage each other to perform their specific functions may be made in the light of the teachings of this application. This invention is therefore intended to include all such modifications, changes, and improvements as fall within the spirit and scope of the attached claims.

Now, therefore, we claim:

1. A steaming device for use with flatirons having an outwardly and downwardly beveled lower edge, comprising a steam soleplate, and means on the device for attachment of the soleplate with its upper surface against the bottom of a flatiron; said attachment means including a rearwardly and upwardly extending portion at the rear of the steam soleplate, a latch pivotally mounted on the rearwardly and upwardly extending portion of the device for rotation on a horizontal axis spaced outwardly beyond the flatiron rear edge and above the level of the flatiron bottom, said latch having a portion extending inwardly against the beveled edge and movable along a line inclined downwardly toward the

flatiron and angularly intersecting the beveled lower edge of the flatiron, and means resiliently urging the latch portion against the beveled edge.

2. A steaming device for removable attachment to a flatiron, comprising a steam soleplate, a rearwardly and upwardly extending hollow supporting member mounted on the soleplate and having enclosing plates on the rear and two sides constituting a substantially enclosed chamber with one open side facing toward the flatiron, a liquid supply tank mounted on the supporting member, and cooperating means for attachment of the device to the flatiron including a latch movably mounted within said supporting member and substantially concealed and protected by the plates of the latter.

3. A steaming device for removable attachment to a flatiron, the device comprising a steam soleplate, a supporting bracket mounted on the soleplate, a liquid supply tank mounted on the bracket and extending over a portion of the flatiron and spaced closely above the portion when the device is attached to the iron, and a latch mounted on the device inside the bracket, one part of the latch being movable for engagement with said flatiron portion beneath the tank.

4. A steaming device for removable attachment to a flatiron, the device comprising a steam soleplate, a rearwardly and upwardly extending supporting bracket mounted on the rear of the soleplate and including a pair of laterally spaced substantially vertical and parallel side plates extending longitudinally of the soleplate, a liquid supply tank mounted on the bracket above the side plates, and a latch mounted on the device and having a movable part between the side plates for engagement with said flatiron, the side plates extending both forwardly and rearwardly beyond said movable part over a substantial horizontal and vertical area between the steam soleplate and tank, whereby the movable part is substantially concealed and protected by the side plates.

5. A steaming device for removable attachment to a flatiron, the device comprising a steam soleplate, a supporting bracket mounted on the soleplate and including a pair of spaced side plates, a liquid supply tank mounted on the bracket above the side plates, and extending over a portion of the flatiron when the device is attached to the iron, and a latch mounted on the device and having a movable part between the side plates and beneath the tank for engagement with said flatiron portion, the side plates extending over a substantial horizontal and vertical area between the steam soleplate and tank, and the movable part being substantially concealed and protected by the side plates and tank.

6. A steaming device for removable attachment to a flatiron comprising a steam soleplate, a supporting member at the rear of the soleplate, a liquid supply tank mounted on the supporting member and having a portion adapted to extend forwardly and overlap the rear of the flatiron, a latch member having a transverse shaft portion pivotally mounted in the supporting member and provided with retaining portions and adapted to extend forwardly between the flatiron and tank and engaging the flatiron beneath the tank, and resilient means engaging

the latch member and urging said retaining portions downwardly against the flatiron.

7. A steaming device for removable attachment to a flatiron comprising a steam soleplate, a supporting member at the rear of the soleplate, one part of the supporting member adapted to extend rearwardly beyond the flatiron and another part adapted to extend forwardly along each side of the flatiron, a liquid supply tank mounted on the supporting member and having a first portion extending forwardly and adapted to overlap the rear of the flatiron and a second portion adapted to extend rearwardly beyond the flatiron, a latch member having a transverse shaft portion pivotally mounted in that part of the supporting member which is adapted to extend rearwardly of the flatiron and provided with retaining portions extending forwardly and adapted to project between the flatiron and tank and engaging the flatiron beneath the tank, and resilient means engaging the latch member and urging said retaining portions downwardly against the flatiron.

8. A steaming device for use with flatirons having an outwardly and downwardly beveled lower edge, comprising a steam soleplate, and means for attachment of the soleplate with its upper surface against the bottom of the iron, said attachment means comprising an upwardly and inwardly inclined retaining member at one end of the soleplate adapted for cam engagement with the beveled lower edge of the corresponding end of the flatiron thereby urging the iron and soleplate against each other in response to relative longitudinal movement of the iron toward said one end of the soleplate, a latch pivotally mounted at the opposite end of the soleplate for rotation on a horizontal axis spaced rearwardly beyond the corresponding other end of the flatiron, said latch having a portion extending inwardly against the beveled flatiron edge when the flatiron and steaming device are assembled and movable along a line inclined downwardly toward the flatiron and angularly intersecting the beveled lower edge of the flatiron thereby having cam engagement with said beveled edge and causing relative longitudinal movement of the flatiron toward said one end of the soleplate in response to downward movement of said latch portion against the beveled edge, and means resiliently urging the latch portion downwardly against said beveled edge and thereby also urging the iron and soleplate toward each other at said corresponding end of the flatiron.
